UNITED STATES PATENT OFFICE.

WALTER H. HENDRICKSON, OF CHICAGO, ILLINOIS.

DESIGN FOR A DENTAL-EQUIPMENT PEDESTAL.

53,590.

Specification for Design.

Patented July 15, 1919.

Application filed March 28, 1919. Serial No. 285,933. Term of patent 14 years.

To all whom it may concern:

Be it known that I, WALTER H. HENDRICKSON, a citizen of the United States, and a resident of Chicago, in the county of Cook and State of Illinois, have invented a certain new, original, and ornamental Design for Dental-Equipment Pedestals, of which the following is a specification, reference being had to the accompanying drawing, forming part thereof.

The figure is a perspective view of a

dental equipment pedestal, showing my new design.

I claim:

The ornamental design for a dental equipment pedestal, as shown.

In witness whereof I have hereunto set my hand and affixed my seal this 26th day of March, A. D. 1919.

WALTER H. HENDRICKSON. [L. S.]

Witness:

JOHN HOWARD McELROY.
